UNITED STATES PATENT OFFICE.

CHARLES K. SHERWOOD, OF NEW YORK, N. Y.

DESIGN FOR A BOTTLE-CAP FASTENER.

SPECIFICATION forming part of Design No. 30,403, dated March 28, 1899.

Application filed March 2, 1899. Serial No. 707,556. Term of patent 7 years.

To all whom it may concern:

Be it known that I, CHARLES K. SHERWOOD, a citizen of the United States, residing at New York, in the county and State of New York, have invented and produced a new and original Design for a Bottle-Cap Fastener, of which the following is a specification, reference being had to the accompanying drawings, showing a part thereof.

10 Figure 1 is a perspective view of the bottle-cap fastener, showing my design; and Fig. 2 is a side elevation of the same.

The leading features of my design are the elongated body and the doubly-curved ends 15 with inward and outward bends, as shown.

The bottle-cap fastener has an elongated

body which when viewed in side elevation appears slightly dishing on top, and the ends of the body are doubly curved—that is to say, each end is bent inward, and said inward bend, which is relatively long, merges in a shorter outward bend, the extreme end of which bend is slightly reduced and when viewed in side elevation appears somewhat rounding. 25

What I claim is—

The design for a bottle-cap fastener herein shown and described.

CHARLES K. SHERWOOD.
